5 Claims. (Cl. 179—171)

This invention relates to band-pass filter circuits and particularly to variable selectivity filter circuits employing crystal resonators coupling two tuned circuits.

According to the invention a band-pass filter comprises two tuned circuits, crystal resonator means coupling said tuned circuits, means for neutralising the capacity of said crystal resonator, means for short circuiting said crystal resonator, and switch means operable to control the effective impedance of said tuned circuits in such manner that in one position of said switch means said tuned circuits are tuned to the series-resonant frequency of said crystal and in another position of said switch means said tuned circuit are tuned one above and the other below said series-resonant frequency.

The means for short circuiting the crystal resonator and the switch means may be so inter-related that the said switch is effective to control the impedance of said tuned circuits when said crystal resonator is not short circuited.

Where the band pass filter is applied to the first inter-valve stage of a multi-stage intermediate frequency amplifier switch means may be provided such that when the crystal resonator is included in the said band-pass filter the value of the coupling in subsequent stages is constant and that when said crystal resonator is short-circuited the value of the coupling is variable whereby the overall selectivity-response is varied.

The invention is illustrated in the accompanying drawing whereof Figure 1 is a circuit diagram of an arrangement in accordance with the invention, and Figure 2 is a circuit diagram of a second embodiment.

In the circuit carrying the invention into effect as applied to the first intervalve stage of an intermediate frequency amplifier, and as illustrated in Figure 1, the anode of a valve V1 is connected as is usual to a tuned circuit comprising an inductance L1 and condenser C1 in parallel, the remote end of the inductance being connected to a source of anode potential. The anode is also capacity coupled by condenser C4 to one electrode of a crystal resonator Q; series resonant at the desired intermediate frequency. The other electrode of the crystal resonator is connected to a tuned input circuit, comprising an inductance L2 and a capacity C2 of a second valve V2 grid bias being applied by way of the inductance of said input circuit. The said other electrode of the crystal is also connected to the capacity element of a neutralising circuit comprising a capacity C3 and inductance L3 in series, 55

the inductive element being coupled to the inductance of the first tuned circuit and connected to the end thereof remote from the anode connection. In addition, the two electrodes of the crystal resonator are connected to the two terminals of a short-circuiting switch S1 and also to two fixed terminals of a change over switch S2. The blade of the change over switch S2 is connected to one terminal of a condenser C5 the other terminal of which is connected to earth. In one position of the change-over switch S2, and when the short-circuiting switch S1 is open, this last mentioned condenser C5 is effectively in parallel with the condenser C1 of the first tuned circuit and the two tuned circuits L1 C1, L2 C2 are then tuned to the intermediate frequency, and in the other position of the change-over switch S2 the last mentioned condenser C5 is removed from the first tuned circuit and connected effectively to parallel with the condenser C2 of the second tuned circuit. In this last condition the first and second tuned circuits L1 C1, L2 C2 are tuned respectively above and below the intermediate frequency to a like amount, depending inter alia upon the value of the condenser C5 transferred. When the crystal is short circuited, this condenser is in parallel with those (C1, C2) in both tuned circuits.

In another embodiment of the invention illustrated in Figure 2, as applied to a multi-stage intermediate frequency amplifier, the change over switch S12 is provided with a plurality of contacts whereby, in one position (position 2) of the switch, the crystal Q is in circuit and the transferrable condenser C5 is effectively in parallel with the capacity C1 of the first tuned circuit, in another position (position 1) the crystal is in circuit and the transferrable condenser C5 is effectively in parallel with the capacity C2 of the second tuned circuit, and in a third position (3) the crystal is short-circuited, and in all these positions the coupling in subsequent intervalve stages remains constant. In subsequent positions of the change over switch S12 the coupling of the subsequent stage or stages is varied. This may be effected by providing the change over switch with a plurality of sets of arms S12', S12'' and sets of contacts (or gang controlling a number of further switches with the change-over switch). The further sets of contacts are connected to tapping points on the inductance L2', L2'' of one tuned circuit of said subsequent stages and the switch arm is connected so as to complete the connection between the inductance and capacity of said tuned circuit.

Where further increase of the overall selectivity of the amplifier, when not using the crystal, is desired it is possible so to arrange matters that the two tuned circuits of the crystal coupled stage are not arranged in parallel relation but function as a single tuned circuit. This may be effected by providing means for varying the effective value of the condenser C_4 to a value which differs from the value of the neutralizing condenser C_3 by an amount necessary to produce any required degree of coupling.

Where it is desired to obtain wide pass-band conditions, the change-over switch S_{12} may be arranged in the subsequent positions (e. g., 4 and 5), or in some of them, to connect damping resistances R_4 and R_5 , of differing values for each position, across the two tuned circuits.

What we claim is:

1. A band-pass filter comprising two tuned circuits, crystal resonator means coupling said tuned circuits, means for neutralising the capacity of said crystal resonator, a pair of contacts each connected to one terminal of the crystal resonator means, a first switch means having a reactance connected therebetween and a point common to both tuned circuits selectively operable to contact one or the other of said pair of contacts to control the effective impedance of said tuned circuits in such manner that in one position of said switch means said tuned circuits are tuned to the series-resonant frequency of said crystal and in another position of said switch means said tuned circuits are tuned one above and the other below said series-resonant frequency, and a second switch means for selectively open-circuiting or short-circuiting the crystal resonator, both switch means being so inter-related that when said second switch is open-circuited the first switch means is effective to control the impedance of said tuned circuits, and when said crystal resonator is short-circuited, in either position of the first switch, the reactance connected thereto is included in parallel with each tuned circuit.

2. A crystal filter of variable band-pass width comprising a pair of tuned circuits, a crystal element for coupling said circuits having one terminal connected to one circuit and a second terminal connected to the other circuit, a reactance element and a resistor each having one terminal connected to a point common to both tuned circuits, and a multi-position switch in successive positions thereof adapted to connect the reactance element across one of said tuned circuits, connect said reactance across the other of said tuned circuits, connect said reactance across both of said tuned circuits and simultaneously short-circuiting the crystal, and to shunt said resistor across the reactance in addition to the last-named connections.

3. A multi-stage amplifier comprising a plurality of cascade-connected electron discharge tubes provided with coupling means between successive tubes, at least one of said coupling means being variable, and at least another of said coupling means comprising a piezo-electric crystal, switch means for selectively short-circuiting the crystal or connecting the crystal to couple successive tubes, and means under the control of said switch means for varying the value of said variable coupling means when the crystal is short-circuited and for maintaining constant the value of said coupling means when the crystal is effective.

4. A multi-stage amplifier comprising a plurality of cascade-connected electron discharge tubes each provided with an input and an output circuit, means for variably coupling an output and an input circuit of certain successive tubes, a piezo-electric crystal constituting the coupling means between an output and an input circuit of other successive tubes, switch means for selectively short-circuiting said crystal or connecting the crystal in coupling relation, and means under the control of said switch means for varying the value of said variable coupling means when the crystal is short-circuited and for maintaining constant the value of said coupling means when the crystal is effective.

5. A multi-stage intermediate frequency amplifier comprising a plurality of cascade-connected electron discharge tubes each provided with a tuned input and a tuned output circuit, a piezo-electric crystal coupling successive tuned output and tuned input circuits, means for variably coupling the next successive tuned output and tuned input circuits, a reactance element and a resistor each having one terminal connected to a point common to both tuned circuits having the crystal coupling therebetween, and a multi-position switch in successive positions thereof adapted to connect the reactance element across one of said tuned circuits, connect said reactance across the other of said tuned

circuits, connect said reactance across both of said tuned circuits and simultaneously short-circuiting the crystal, and to shunt said resistor across the reactance in addition to the last-named connections, a second multi-position switch controlled in unison with the first switch and associated with the variable coupling means so constructed and arranged that in the first three positions the degree of coupling is maintained constant and in the next position the coupling is varied.
